UNITED STATES PATENT OFFICE.

JOHN L. ZANDER, OF NEWARK, NEW JERSEY, ASSIGNOR TO CHARLES C. SANDER, OF IRVINGTON, NEW JERSEY.

GALVANOMETER.

1,098,871.

Specification of Letters Patent. Patented June 3, 1914.

Application filed April 30, 1912. Serial No. 694,132.

To all whom it may concern.:

Be it known that I, JOHN L. ZANDER, a citizen of the United States, residing at Newark, in the county of Essex and State of New Jersey, have invented certain new and useful Improvements in Galvanometers, of which the following is a specification.

My invention relates to improvements in galvanometers which are designed for measuring electric currents and are particularly adapted for use as electric thermometers or as mille volt meters, the object of the invention being to provide an improved arrangement of coils mounted upon a shaft and moving respectively upon a straight and inclined portion of a magnetized core, whereby the difference in the electro-motive force causes the positioning of the coils with relation to the core while one of said coils operates to return the shaft to normal position and dispenses with the necessity for springs or other mechanical mechanism for the purpose.

A further object is to provide improvements of this character which enable the employment of an ordinary dry cell to energize the coils.

A further object is to provide a simple construction of parts which are readily accessible, and which are not liable to get out of order, but which can be readily repaired in the event of injury.

With these and other objects in view, the invention consists in certain novel features of construction and combinations and arrangements of parts, as will be more fully hereinafter described and pointed out in the claims.

In the accompanying drawings: Figure 1 is a vertical longitudinal section of a galvanometer embodying my invention, Fig. 2 is a diagrammatic view illustrating the circuits, Fig. 3, is a plan view of the device with the cover removed. Fig. 4, is a plan view of the fixed magnet. Fig. 5, is a view in side elevation of the bracket 8, and the mechanism carried thereby. Fig. 6, is a perspective view illustrating the shaft 12, and the coils carried thereby. Fig. 7, is a perspective view of the core 13.

My improved galvanometer is supported in a casing 1 preferably having a horizontal partition 2 and a removable cover 3, the latter provided with a slot 4 through which

the readings may be made. In the lower 55 chamber of casing 1, a dry cell battery 3^a is provided, and is connected up in electric circuit with my improvements as will be hereinafter described. On top of the partition 2, a fixed magnet 5 is located, and its poles 6 are curved concentrically on their inner faces and are preferably connected by a metal bar 7. A bracket 8 is secured by screws 9 to the pole pieces 6, and at its upper and lower ends is made with inwardly 65 projecting extensions 10 in which bearings 11 are provided for the ends of a vertical rotary shaft 12.

A curved core 13 of soft iron is secured between its ends by screws 14^a to the bracket 70 3, and is positioned with its outer surface spaced throughout from the pole pieces 6, whereby a uniform air gap is formed between the said core and the pole pieces. The core 13 is formed of a strip of soft iron 75 having one end thereof tapered as shown clearly in Figs. 5 and 7, and the whole strip bent into cylindrical form. This is arranged between the poles of the magnet with the portion of uniform cross section 80 opposite one pole and that of diminishing cross section, that is the tapered portion, opposite the other pole. By this construction and arrangement the core becomes polarized due to the induced magnetism, and the 85 magnetic field between the pole pieces 6 is distorted due to the reluctance between the adjacent ends of the split cylindrical core, and the great permeability of the opposite side of the core. It will be understood that 90 the field between the side of the core of uniform cross section and the adjacent pole 6 will be more uniform than that between the tapered portion and its adjacent pole 6 which varies in strength with the taper. 95 The metal bracket 8 connects the pole pieces on the side opposite the bar 7, and the latter is provided for the purpose of connecting the pole pieces 6 when the device is being assembled.

On shaft 12 arms 14 are fixed between their ends, and at their ends support coils 15 and 16. The former I shall term the "current coil" because it is directly connected to the battery and operates to maintain the 105 coils in normal or zero position. This coil is arranged to surround the portion of the core of uniform cross section, and tends to return

the same to that position, dispensing with the necessity for mechanical means of any sort. The coil 16, which is arranged to surround the tapered portion of the core, I shall term the "measuring coil" because this coil by reason of the varying electro-motive force assumes a position on the inclined end of the core 13 in accordance with such electro-motive force. In other words, while the air gap between the coil 15 and the core 13 is always the same, the tendency of this coil is to hold the shaft in a predetermined position which will be zero on the scale. The other coil 16, however, will tend to move on the core in accordance with the fluctuations in the electro-motive force, and will therefore turn the shaft 12. This shaft 12 is provided with a pointer 17 which registers with a scale 18 secured to a bracket 19 secured to the fixed magnet 5. This pointer 17 is angular in cross section with its base flange cut away near its point so as to present a knife edge to the scale. An extension 20 is provided on the pointer, and this extension is screw-threaded for the reception of a counterbalance weight 21, so that the pointer does not tend to overbalance or exert undue friction on the shaft.

On one end of the casing 1, three binding posts 22, 23, and 24, are provided. Binding post 23 constitutes the positive pole and binding post 22 the negative, while binding post 24 is a dead pole except when connected in circuit with what I term a "bulb" 25. This bulb 25 may be made in any way which will stand the temperatures and conditions to which it is to be exposed and vary the resistance of its circuit according to its change of temperature. It may comprise a coil preferably of nickel wire in a metal case as indicated in Fig. 1, said case merely acting as a protecting cover for the coil, the coil being sensitive to changes of temperature. The bulb is illustrated merely to designate a part which is sensitive to changes of temperature. It is well known that varying temperatures cause variations in resistance, and this bulb is sensitive to these variations and is connected electrically with the circuit, preferably by means of suitable binding posts located on the casing. When not desired, it is simply necessary to break the connection between the post 24 and the bulb so as to prevent wasting of the current.

A bar 26 is secured to bracket 8 and is provided at its ends with insulating blocks 27 and 28. Block 27 is provided with two conductors 29, and these conductors are connected to collars 30 mounted upon insulated sleeves 31 fixed to shaft 12. These collars 30 are connected in circuit with coils 15 and 16 as seen most clearly in Fig. 5. An intermediate collar 32 is secured directly to shaft 12, and is connected with a contact 33 on

block 28. By reason of this arrangement of electric conductors, and the fact that they are of extremely fine gage wire, the tension or weight of the wires will have no appreciable effect upon the rotary position of the shaft, particularly as the angle of movement of the indicator is small. In other words, to connect wires to the coil except by first connecting with the spindle or center of the arc through which the coils move, there is bound to be some twisting or tension of the wires however small they may be.

By reference to the diagram shown in Fig. 9, it will be seen that at certain points in the circuit, resistance coils 34 are provided, the function of which will appear hereinafter.

From the battery 3^a the current flows through conductor 43 to binding post 22, thence through conductor 42, resistance 34^b, conductor 41 and conductor 40 to the post 12 and coil 15, thence through the conductors 39 and 38, resistance 34 and conductor 37 to binding post 23, thence through conductor 36 to the battery. The bulb 25 is connected to the circuit in the following manner: A conductor 44 connects one end of the coil within the bulb with conductor 37 as at 35, and a second conductor 45 connects the other end of the coil with the binding post 24. When the bulb is connected, as described, the current divides at 12, part passing through the coil 15 and its circuit above described and part passing through coil 16, conductor 46 to post 24, thence through 45 to the bulb, through 44 to 37, to post 23 and to the battery through conductor 36. To make the indicator move more steadily and prevent sudden jumps and banging I provide a shunt 50 in the circuit to the coil 16 connected to the conductors 40 and 41 at 47 and to the conductor 46; and a shunt 49 in the circuit to the coil 15. The shunt 50 is provided with a resistance coil 34^c and the shunt 49 with a resistance coil 34^a. Coils 34^a and 34^b are used to calibrate the instrument. The shunt 50 is only employed when the device is too sensitive, in order that part of the current may pass through said shunt instead of through the coil 16, and the coil 34^c is arranged in this shunt so that the shunt will not abnormally reduce the current in the coils 16. The coil 34 in the circuit of the coil 15 balances the resistance of the coil in the bulb 25 which is in the circuit of the coil 16, and also insures the passage of the current in the proper direction through the conductor 38.

The bulb 25 is adapted to be placed in a furnace, kiln or anywhere it is desired to ascertain the temperature, and the increase or decrease of temperature increases or decreases the resistance of the coil within the bulb and consequently of the circuit including the bulb 25 and coil 16. Hence the cur-

rent in the coil 16 is varied in proportion to the temperature. The reaction between the variable magnetic condition of the coil 16, due to the variation of the current therein and the variable magnetic field at the tapered portion of the core, causes the indicator to move.

It will thus be seen that I provide on a single shaft, two coils, one operating as a current coil holding the parts in normal position, and the other coil as a measuring coil which is movable upon the inclined end of the core, and by reason of the variations in the electro-motive force assumes its position on this core in accordance with the varying air gap between the coil and the end of the core.

From the left or positive side of battery 3^a, the current flows through conductor 36 to binding post 23, thence through conductor 37, resistance 34, conductor 38, and conductor 39 to coil 15, thence to post 12, thence through conductors 40 and 41, resistance 34^b, and conductor 42 to binding post 22, thence through conductor 43 to the right hand or negative side of battery 3^a. Included in this circuit is the bulb 25 as will now be explained. A conductor 44 connects one end of the coil within the bulb with conductor 37 as shown at 35. A second conductor 45 connects the other end of the coil with binding post 24, and a conductor 46 having a resistance 34^c therein, connects with conductors 40 and 41 at the point 47. Conductor 46 is also connected directly to coil 16 by a conductor 48. The varying resistance due to the difference of temperature, compels the coils 15 and 16 to assume a position on the core 13. When the temperature changes, the resistance varies, and the coils move on the core, compelling the pointer to swing. Coil 15 is also connected by a conductor 39 with conductor 38, and a resistance coil 34^a is located between the ends of the conductor 49, connecting conductors 38 and 39 with conductor 42, so that a portion of the current is shunted through this resistance 34^a. The several resistance coils 34, 34^a, 34^b and 34^c are used to render the instrument extremely sensitive and variations may be made in the number and location of such coils. The several resistance coils 34 cause the instrument to become sensitive, and in varying this resistance, an extremely sensitive instrument is had.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what

I claim as new and desire to secure by Letters Patent is:

1. In a device of the class described, a magnet having oppositely disposed poles and an intervening air gap, a curved core 70 within said gap, one portion of said core being of variable cross section, a rotary element mounted concentrically with relation to said core, a pair of coils carried by said rotary element, one of said coils surrounding a portion of the core with uniform cross section and the other coil surrounding the portion of the core of variable cross section, both of said coils being adapted to be connected to a source of current supply and the coil surrounding the portion of the core of variable cross section being adapted to be connected in circuit with a variable resistance, substantially as described.

2. In a device of the class described, a 85 magnet having oppositely disposed poles and an intervening air gap, an annular core of soft iron arranged in said air gap and spaced uniformly from said poles, the portion of said core opposite one of said poles 90 being of uniform cross section and the portion thereof opposite the other pole being of variable cross section, a rotary element mounted concentrically within said core, a pair of coils mounted on said rotary element 95 and surrounding the above mentioned portions of the core respectively, both of said coils being adapted to be connected to a source of current supply and the coil surrounding the portion of the core of variable 100 cross section being adapted to be connected in circuit with a variable resistance, substantially as described.

3. In a device of the class described, a magnet having oppositely disposed poles 105 and an intervening air gap, an annular core of soft iron in said gap, one portion of said core being of uniform cross section and a portion thereof being of variable cross section, a rotary element arranged concentrically within said core, a pair of coils carried by said rotary element and surrounding the above mentioned portions of said core respectively, a circuit from each of said coils adapted to be connected to a source of 110 current supply, a shunt in each of said circuits, a fixed resistance in each of said shunts and the circuit to said coil surrounding the portion of the core of variable cross section, being adapted to have a variable 115 resistance interposed therein, substantially as described.

4. In a device of the class described, a permanent horse-shoe magnet provided with oppositely disposed poles, an annular 125 soft iron core arranged in the air gap between said poles, the portion of said core opposite one of said poles being of uniform cross section and the portion of the core opposite the other pole being of variable cross 130

- section, a bar connecting said poles and arranged upon the side of said core having the smallest cross section, a bracket connecting the poles upon the opposite side of said core from said bar, a rotary element supported by said bracket and arranged concentrically within said core, a pair of coils carried by said rotary element and surrounding the said portions of said core respectively, both of said 10 coils being adapted to be connected to a source of current supply and the coil surrounding the portion of the core of variable cross section being adapted to be connected in circuit with a variable resistance and an indicator 15 connected to said rotary element, substantially as described.
5. In a device of the class described, a permanent horse-shoe magnet provided with oppositely disposed poles, an annular soft 20 iron core arranged in the air gap between said poles, the portion of said core opposite one of said poles being of uniform cross section and a portion of the core opposite

the other pole being of variable cross section, a bar connecting said poles and arranged upon the side of said core having the smallest cross section, a bracket connecting the poles upon the opposite side of said core from said bar, a rotary element supported by said bracket and arranged concentrically within said core, a pair of coils carried by said rotary element and surrounding the said portions of said core respectively, conductors mounted upon said bracket and insulated therefrom, collars on 30 said rotary element, conductors connecting the first mentioned conductors and said collars, and conductors connecting said collars and said coils, substantially as described.

In testimony whereof I have signed my name to this specification in the presence of two subscribing witnesses.

JOHN L. ZANDER.
